Primary Examiner — Leanne Was-Englehart*Assistant Examiner* — Yelizaveta Y Masalimova(74) *Attorney, Agent, or Firm* — Marshall A. Lerner; Steven J. Kim; Kleinberg & Lerner, LLP**CLAIM**

The ornamental design for a shoe as shown and described.

DESCRIPTION

FIG. 1 is a front perspective view of a shoe in accordance with my new design;

FIG. 2 is a front view thereof;

FIG. 3 is a rear view thereof;

FIG. 4 is a left side thereof;

FIG. 5 is a right side thereof;

FIG. 6 is a top view thereof; and,

FIG. 7 is a bottom view thereof.

Broken lines shown in the drawing represent portions of the shoe midsole periphery, the shoe outsole bottom and the environmental structure of the shoe upper which form no part of the claimed design.
